UNITED STATES PATENT OFFICE.

JEAN HARLÉ, OF ROUEN, FRANCE.

DETONATING-FUSE.

1,306,895.

Specification of Letters Patent. Patented June 17, 1919.

No Drawing.

Application filed June 29, 1914. Serial No. 848,071.

To all whom it may concern:

Be it known that I, JEAN HARLÉ a citizen of the French Republic, residing at Rouen, in the French Republic, have invented certain new and useful Improvements in Detonating-Fuses, of which the following is a specification.

This invention relates to a detonating fuse characterized by the arrangement according to which the explosive filling of the fuse consists either entirely or partly of tetranitropentaerythrite of the formula:—

15

This explosive which is generally known can easily be produced in a perfectly pure state and in this case it possesses an extraordinary stability against heat and moisture.

20 This explosive is one of the most powerful explosives known; it detonates easily under the influence of an ordinary primer, for example of a primer of fulminate of mercury.

25 The fuse is made according to the usual methods. If a detonating tube with metal cover is to be made the tetranitropentaerythrite is preferably mixed with an explosive substance which melts more easily than the tetranitropentaerythrite, for example trinitrotoluene so that the tubes can be filled without any difficulty, said tubes being then drawn out in the well known manner. This method of filling can be used also for fuses, the principal explosive charge of which is not of tetranitropentaerythrite but of any explosive which is also not easily fusible.

30 The explosive substance mentioned is further particularly adapted for the manufacture of flexible fuses with textile covers. It is generally known that, with the explosives used actually, it is impossible to obtain a regular working as far as the flexible detonating fuses with textile covers are concerned. The explosives which have been used for this purpose are not sufficiently sensitive to ignite with certainty or they

are not sufficiently pure and consequently detonate irregularly.

35 The tetranitropentaerythrite being obtained at the state of perfect purity and remaining at the same time stable and adapted to ignite regularly and easily permits of making flexible detonating fuses of perfect sure and regular working, said substance being either used alone or admixed with other substances. The manufacturing of said fuses is effected in the well known manner by pouring the explosive in powder to the tubular envelop in quantities corresponding with the progress of manufacture.

40 The tetranitropentaerythrite can either be used alone or admixed in convenient proportions with another substance such as the nitro-benzin, nitrotoluene, phenols and nitrated amins. The envelop of the fuse can be of any convenient material either metallic, textile or the like.

45 Further advantages of the detonating fuses made according to the present invention are: absolute stability against the heat and the moistness, etc. If other substances are admixed with the tetranitropentaerythrite, various degrees of power and sensitivity can be obtained and the qualities of the fuses can be varied within very wide limits.

50 I claim:—

1. A detonating fuse for the instantaneous transmission of detonation waves from a primary detonator to an explosive charge, such fuse comprising a tube filled with a detonating composition comprising as its essential constituent, tetranitropentaerythrite in a highly purified state.

55 2. A detonating fuse for the instantaneous transmission of detonation waves from a primary detonator to an explosive charge, such fuse comprising a tube filled with a detonating composition comprising as its essential constituents, tetranitropentaerythrite in a highly purified state and an explosive substance which melts at a lower temperature than said tetranitropentaerythrite.

60 3. A detonating fuse for the instantaneous

transmission of detonation waves from a primary detonator to an explosive charge, such fuse comprising a tube made of a textile material, filled with a detonating composition comprising as its essential constituent, tetrinitropentaerythrite in a highly purified state.

In witness whereof I have hereunto set my hand in the presence of two witnesses.

JEAN HARLÉ.

Witnesses:

CHAS P. PRESSLY,

ALBERT DE CARSALADE.
